(57) **CLAIM**

The ornamental design for a mascara shield, as shown and described.

DESCRIPTION

FIG. 1 is a front right top perspective view of a first embodiment of the makeup shield, showing my new design; FIG. 2 is a front elevation view of the first embodiment of the makeup shield;

FIG. 3 is a rear elevation view of the first embodiment of the makeup shield;

FIG. 4 is a left elevation view of the first embodiment of the makeup shield;

FIG. 5 is a right elevation view of the first embodiment of the makeup shield;

FIG. 6 is a top view of the first embodiment of the makeup shield;

FIG. 7 is a bottom view of the first embodiment of the makeup shield;

FIG. 8 is a front left top perspective view of a second embodiment of the makeup shield;

FIG. 9 is a front elevation view of the second embodiment of the makeup shield;

FIG. 10 is a rear elevation view of the second embodiment of the makeup shield;

FIG. 11 is a left elevation view of the second embodiment of the makeup shield;

FIG. 12 is a right elevation view of the second embodiment of the makeup shield;

FIG. 13 is a top view of the second embodiment of the makeup shield; and,

FIG. 14 is a bottom view of the second embodiment of the makeup shield.
